UNITED STATES PATENT OFFICE.

CLARK T. HENDERSON, OF MILWAUKEE, WISCONSIN, ASSIGNEE TO THE CUTLER-HAMMER MFG. CO., OF MILWAUKEE, WISCONSIN, A CORPORATION OF WISCONSIN.

MOTOR-CONTROLLER.

945,093.

Specification of Letters Patent. Patented Jan. 4, 1910.

Application filed April 23, 1909. Serial No. 491,571.

To all whom it may concern:

Be it known that I, CLARK T. HENDERSON, a citizen of the United States, residing at Milwaukee, in the county of Milwaukee and State of Wisconsin, have invented new and useful Improvements in Motor-Controllers, of which the following is a full, clear, concise, and exact description, reference being had to the accompanying drawing, forming a part of this specification.

My invention relates to improvements in controllers for electric motors.

More particularly it relates to controllers in which the starting resistance is controlled by means of a plurality of independent switches, each switch being provided with a throttling device for preventing closure thereof while there is an excessive flow of current through the motor. In my prior patent, No. 890,979, granted June 16, 1908, I have disclosed a controller of this type in which the winding of each of the throttling devices is connected in series with the motor armature and the resistance sections controlled by its own and succeeding resistance switches.

According to my present invention, instead of connecting the windings of the throttling devices in series with the sections of starting resistance, controlled by their corresponding resistance switches, I connect the same in parallel therewith. I also provide means whereby each of the throttling devices may be adjusted to respond under different predetermined conditions.

In order to more clearly set forth the characteristic features of my invention, I shall describe the system of control diagrammatically illustrated in the accompanying drawing, which embodies my invention in certain forms.

Of course, my invention is susceptible of various modifications.

The system of control illustrated includes a main switch 1, resistance switches 2, 3, 4 and 5, and throttling switches 6, 7, 8 and 9, one for each of the resistance switches. The switches 1, 2, 3, 4 and 5, are provided with operating windings 1^a, 2^a, 3^a, 4^a and 5^a, respectively. The switches 2, 3, 4 and 5, are arranged to control resistances R², R³, R⁴ and R⁵, respectively. These resistances are arranged in circuit with the motor, which is illustrated as provided with an armature A and series field winding F. The circuit

arrangement for the operating winding of the resistance switches is substantially the same as that illustrated in my former patent. The resistance switches 2, 3 and 4, are provided with auxiliary contacts 10, 11 and 12, respectively, each of which is adapted to engage a stationary contact to complete the circuit of the operating winding of the next succeeding switch, provided that the throttling device of said switch has not responded in the meantime. The throttling switches 6, 7, 8 and 9, are provided with controlling windings 6^a, 7^a, 8^a and 9^a, respectively, each of which is connected in parallel with the section of starting resistance controlled by its corresponding resistance switch. The windings of the throttling switches 6 and 7 are shown as provided with devices 16 for connecting one terminal of each to its corresponding resistance section at different points, while the windings of the throttling switches 8 and 9 are shown as having variable resistances 17 connected in series therewith. The purpose of these arrangements will be hereinafter set forth.

I shall now briefly describe the operation of the system of control illustrated. Current is supplied from main lines 20 and 21 through a main line switch 22. The operation of the various switches is initially controlled by a switch 23, which, when closed, first completes a circuit from main line 20 by conductor 24 through the operating winding 1^a of the main switch 1 by conductor 25 to conductor 26 and thence to the negative line 21. Upon energization of the winding 1^a the main switch 1 is closed, thereby completing the motor circuit from conductor 24 through the main switch 1 by conductor 27, thence dividingly through the operating winding 6^a of the throttling switch 6 and resistance section R², thence dividingly through each of the resistance sections R³, R⁴ and R⁵, and the windings of their corresponding throttling switches, by conductor 28 through the series field winding F, motor armature A, and back to the negative line. The motor is thus started with all of the starting resistance in circuit. Inasmuch as the windings of the throttling switches are connected in parallel with their corresponding resistance sections, which are in series with the motor, a portion of the motor current will flow through said windings, the amount of current flowing through the wind-

ings depending upon the relative resistances of the parallel circuits. It will thus be seen that the relative resistances of the parallel circuits may be so proportioned that the throttling switches will respond only when there is an excessive flow of current through the motor. Hence, should there be an excessive flow of current through the motor, when the main switch 1 is closed, the throttling device 6 would respond, thereby interrupting the circuit of the winding 2^a. On the other hand, if the motor was able to take care of the in-rush of current upon the closure of the main switch 1, then the throttling device 6 would not respond and circuit would be completed from switch 23, when fully closed, by conductor 30 through the throttling switch 6, thence through the winding 2^a of the resistance switch 2 and conductors 25 and 26 to the negative line 21. The switch 2 would thereupon close, thereby short-circuiting the resistance section R². The resistance R² would thus be removed from the motor circuit, and current would flow from the main switch through the resistance switch 2, thence dividingly through the remaining resistances and their corresponding throttling windings to the motor. Closure of the switch 2 causes the auxiliary contact 10 to engage its stationary contact, thereby completing the circuit of the winding 3^a from main switch 1, auxiliary switch 10, conductor 31 to throttling switch 7 by conductor 32 through the winding 3^a, and thence by conductors 25 and 26 to the negative line. If, however, upon the removal of the resistance R² from the motor circuit, there was an excessive flow of current through the motor, the throttling device 7 would respond, thereby interrupting the circuit of the winding 3^a. This would occur before the winding 3^a was sufficiently energized to close the switch 3, and consequently said switch would not be closed until normal conditions were restored and the throttling switch 7 had returned to closed position. Closure of the switch 3 short-circuits the resistance R³ and completes the circuit of the winding 4^a of the switch 4, from auxiliary contact 11 by conductor 33 through switch 8, (if closed), by conductor 34 through the winding 4^a to conductor 25. Of course, if the throttling switch 8 responded, the winding 4^a would not be energized until normal conditions were restored. Closure of the switch 4 short-circuits the resistance R⁴ and completes a circuit from auxiliary contact 12 by conductor 35 through the throttling switch 9 by conductor 36 through the winding 5^a of the switch 5. The switch would thereupon close as soon as the relay switch returned to closed position, if the same had in the meantime responded to an excessive flow of current. Upon closure of the switch 5 the motor cir-

cuit is completed from main switch 1 by conductor 37 through switch 5 and thence through the motor. Each of the resistance switches not only short-circuits a portion of the starting resistance, but also short-circuits the winding of its corresponding throttling switch, thereby rendering the same inoperative.

I shall now describe the purpose of the members 16 for connecting one terminal of each of the throttling windings 6^a and 7^a to their respective resistance sections at different points. As previously pointed out, the amount of current flowing through each of the throttling windings depends upon the relative resistances of the two parallel circuits. It is obvious more current would flow through each of the throttling windings when connected in parallel to an entire section of resistance than when connected in parallel to only a portion thereof. Hence, if the members 16 were moved to the left they would decrease the resistance in shunt to the throttling windings, thereby decreasing the flow of current therethrough. It will, therefore, be seen that this arrangement enables me to adjust the throttling devices to respond under different predetermined conditions. The same result may be accomplished by means of the variable resistances 17 arranged in series with the throttling windings 8 and 9. By increasing the amount of resistance in series with the throttling windings, the flow of current therethrough would be decreased, and vice versa. Both of these arrangements, it will be observed, enable me to adjust each of the throttling devices independently of the remainder.

Of course, other means might be employed for adjusting the relay devices which would fall within the scope of my invention.

Having thus described my invention what I claim as new and desire to secure by Letters Patent, is—

1. In a controller for electric motors, in combination, a resistance, an automatic switch for controlling said resistance, and an electroresponsive throttling device, having its winding connected in parallel with a predetermined amount of said resistance, said throttling device being adapted to prevent the operation of said switch while there is an excessive flow of current through the motor.

2. In a controller for electric motors, in combination, a resistance, an automatic switch for controlling said resistance, and an electro responsive throttling device having its winding connected in parallel with a predetermined amount of said resistance, said throttling device being adapted to prevent the operation of said switch while there is an excessive flow of current through the motor, and means for adjusting said throttling device.

tling device to respond under different predetermined conditions.

3. In a controller for electric motors, in combination, a starting resistance, a plurality of automatically operated switches for gradually removing said starting resistance from circuit, and a plurality of electroresponsive throttling devices for arresting the successive operation of said switches upon an excessive flow of current through the motor, the controlling winding of each of said throttling devices being connected in parallel with a portion of said resistance.

4. In a controller for electric motors, in combination, a starting resistance, a plurality of automatically operated switches for gradually removing said starting resistance from circuit, a plurality of electroresponsive throttling devices for arresting the successive operation of said switches upon an excessive flow of current through the motor, the controlling winding of each of said throttling devices being connected in parallel with a portion of said resistance, and means for adjusting said throttling devices to respond under different predetermined conditions.

5. In a controller for electric motors, in combination, a plurality of successively operated resistance switches, a section of resistance controlled by each of said switches, a plurality of electroresponsive throttling devices, one for each of said switches, each of said throttling devices having its controlling winding connected in parallel with a predetermined amount of the resistance controlled by its corresponding switch and being adapted to prevent the operation of its corresponding switch while there is an excessive flow of current through the motor.

6. In a controller for electric motors, in combination, a starting resistance, a plurality of automatically operated switches for gradually removing said starting resistance from circuit, a plurality of electroresponsive throttling devices for arresting the successive operation of said switches upon an excessive flow of current through the motor, the controlling winding of each of said throttling devices being connected in parallel

with a portion of said resistance, and means for adjusting the flow of current through the windings of said throttling devices to cause the same to respond under different predetermined conditions.

55

7. In a controller for electric motors, in combination, a starting resistance, a plurality of electromagnetically operated switches for gradually removing said resistance from circuit, a plurality of electroresponsive relay switches, one for each of said resistance switches, each of said relay switches having its operating winding connected in parallel with a portion of said resistance and being adapted to prevent the operation of its corresponding resistance switch while there is an excessive flow of current through the motor, and a variable resistance adapted to be connected in circuit with the winding of each of said relay switches to cause the same to respond under different predetermined conditions.

60

8. In a controller for electric motors, in combination, a plurality of electromagnetically operated resistance switches, each of said switches when closed being adapted to close the circuit of a succeeding switch, a resistance controlled by each of said switches, a plurality of electroresponsive relay switches, one for each of said resistance switches, each of said relay switches having its winding connected in parallel with the resistance controlled by its corresponding resistance switch and being adapted to prevent the closure of its corresponding resistance switch while abnormal conditions exist, each of said resistance switches, when closed, being adapted to short circuit the winding of its corresponding relay switch to render the same inoperative, and means for adjusting said relay switches to respond under different predetermined conditions.
